JOURNAL BOX LID

Albert O. Buckius, Cleveland Heights, Ohio, assignor to National Malleable and Steel Castings Company, Cleveland, Ohio, a corporation of Ohio

Application September 2, 1942, Serial No. 457,037

8 Claims. (Cl. 308—47)

1

This invention pertains to a journal box lid for closing the opening at the front end of a railway journal box.

It is an object of the invention to construct a two-piece journal box lid retaining all of the advantages of previous lids and which is considerably less expensive to produce. Contributing to the reduction in the cost of producing the lid is the elimination of all machining operations from the parts. Moreover, the parts are so arranged that a coil spring can be used which is not bent and ground flat on the ends, thus saving the cost of this grinding operation.

Another advantage of the invention is that the closure part of the lid can not become displaced from the housing, even though the spring that normally maintains the parts in assembled relation is broken and even though the spring may be broken into pieces small enough that they become lost from the lid. Means is also provided for maintaining the closure part of the lid in such relation to the mouth of the journal box opening that the closure will return to the same position on the mouth opening at successive openings and closings of the lid.

Other objects and advantages of the invention will be understood from the following detailed description, taken in conjunction with the drawings, in which:

Figure 1 is a side elevation of a journal box lid embodying the invention, applied to a journal box.

Figure 2 is a vertical sectional view taken on the center line of the lid and accompanying journal box, the lid being shown in closed position in full lines and in opened position in dot-dash lines.

Figure 3 is a transverse sectional view taken on line 3—3 of Fig. 2.

Figure 4 is a front view of the lid with portions of the housing and closure members broken away.

Figure 5 is a partial view of an end of the lever.

Figure 6 is a partial view showing the spring seat in the bottom of the closure member.

Figure 7 is a view of the spring, showing the unbent and unground ends thereof; and

Figure 8 is a partial sectional view of the spring seating portion of the closure member, showing the spring before torsion is placed on it to maintain the closure member in a given relation to the housing member.

In the drawings the journal box 10 has the usual hinge lug 11 formed with an opening to receive the hinge pin 14 which joins the lid to the journal box. The two-part lid comprises a housing 12 having openings 13 therein for receiving

2

the hinge pin 14. At the lower end of the housing is an outwardly extending spherical protuberance 15 with flanges 16 and 17 on either side thereof. The closure member 18 is formed with a U-shaped yoke 19 extending outwardly from the closure member. On the inner side of member 19 is a spherical socket 20 adapted to receive the spherical protuberance 15 on the housing member to form a pivotal connection between the closure and housing members. On either side of socket 20 and adjacent flanges 16 and 17, the yoke 19 is formed with flanges 21 and 22 which serve to limit pivotal movement of the closure member in the plane of the journal box opening and also limit longitudinal movement of the closure member relative to the housing.

On the inner wall of housing member 12 is a spherical socket 23 adapted to receive a ball projection 24 of spring lever 25 for pivoting the lever 25 on the housing member. The upper end 26 of the lever engages forward surface 27 of hinge lug 11 in the usual manner. The lower end of the lever is formed with a pocket 28 adapted to receive one end of spring 29. Closure member 18 is depressed 30 inwardly at its central portion to form a pocket receiving the other end of spring 29.

It has been customary in previous journal box lids of this type to bend and grind the ends of the coil spring flat. However, this resulted in a loss 30 of the use of approximately one-half of a coil at each end of the spring. In the present lid by using a coil spring with unbent and unground ends, the material is used more efficiently since the two ends by being left unbent and unground, 35 have the result of increasing by approximately one the number of effective coils in the spring. Thus with a spring of this construction the travel from free height to solid height is greater than with a spring of equal free height in which the 40 ends have been bent and ground flat.

To provide some stability to the spring when it is in operating position bottom wall 33 of pocket 30 is sloped relative to the center line of the spring so that a portion of the bottom coil is in contact 45 with said wall. Likewise wall 34 of pocket 28 is sloped to provide some contact with the opposite end of the spring. Abutments 37 and 38 are formed in pockets 28 and 30 respectively to engage the ends of the coils of the spring and prevent rotation thereof about its longitudinal axis. These abutments are formed by sloping projections 35 and 36 which projections are spaced from the adjacent coils of the spring so that there is no contact therebetween during normal operation 50 of the device. Thus with the arrangement

shown the last coil at each end of the spring, in addition to the remaining coils, is under initial compression and in case of spring breakage the end coils as well as the remainder of the spring are available to compensate for the loss in deflection caused by the broken coil.

Although spring breakage is not a common occurrence, considerable damage may result if means is not provided to prevent loss of the closure member from the lid when a spring breaks. Loss of the closure member would permit dirt and moisture to enter the box and contaminate the oil and thereby damaging the bearing. In the present invention the housing, closure member and the lever are held in operative relation solely by means of spring 29. By the use of a coil spring with unbent and unground ends sufficient initial compression can be placed on the spring within the space limitations present, that breakage of a single coil will not eliminate all of the initial compression of the spring. Moreover, even though the spring breaks in several pieces allowing the housing member to move toward the closure member, flange 17 will prevent the closure member from dropping downwardly relative to the housing. In the event of breakage of the spring to such an extent that there is no initial compression remaining, the lever and housing will move by gravity toward the closure member, since the lid as a whole is at an angle to the vertical. Even if the lever and housing were to move toward the closure until the bottom end of the lever contacted the adjacent surface of the closure member, flange 17 would still be in overlapping relation to flange 22 of the closure member, thus preventing the latter from moving downwardly and falling off of the journal box. In addition I provide other means between the lever and the closure member for preventing loss of the closure member. Extending downwardly from the lower end of the lever is a projection 40 having an opening 41 which is adapted to receive a projection 42 on the closure member in the event that spring breakage permits the lever to move a sufficient distance toward the closure member. In this connection it will be observed that socket 23 on the housing terminates in inward projections 43 and 44 which overlap ball 24 on the lever. Thus the lever may move a limited amount towards the closure member without ball 24 being displaced from its socket 23.

Flanges 16, 17 and 21, 22 have another function than that of preventing separation of the housing and closure members. It will be observed that the clearance between these flanges is small and only sufficient to permit a limited amount of universal pivotal movement between the housing and closure so as to assure proper seating of the closure on the journal box. In opening the lid, if it were not for these flanges the closure member would be rotated relative to the housing to a considerable extent. However, flanges 16 and 17 engage flanges 21 and 22 after a limited amount of relative angular movement between the housing and closure members and thereafter the two members move as a unit to opened position of the lid. In closing the lid flange 50 at the upper end of the closure member engages the housing and prevents further relative rotation of the members so that they will move to closed position as a unit.

The steps in assembling the various parts of my journal box lid are as follows: Spring 29 is first placed in pocket 30 of the closure member and compressed by means of a suitable tool a suf-

ficient amount to permit the lower end of lever 25 to be placed on the outer end of the spring. The lever and spring are then forced toward the closure member until the spring is compressed to its solid height. When in this position there is sufficient room between the outer surface of the lever and the inner surface of yoke 19 to slide flange 17 of the housing member between the yoke and lever. During this step in the assembly, the upper end of the housing is tipped away from the closure member and then gradually swung toward the closure member as flange 17 and ball 15 progressively slide between the yoke and the pocket 34 of the lever. When flange 17 has passed the inner end of flange 22, ball 15 may be moved up into its position in socket 20. Spring 29 is then released and the assembly is complete. In applying the lid to a journal box a wedge may be inserted between the inner wall of housing 12 and pocket 34 of the lever which will force the upper end of the lever toward the housing a sufficient amount to permit pin 14 to be passed through the openings in the housing and journal box.

Lids are sometimes made with corrugations on the journal box-engaging surface as shown at 51. These corrugations wear into the journal box face and provide a tight seal which keeps out dirt. However, if corrugations are used, means must be provided to make certain that the lid seats in the same place upon successive closings thereof, otherwise the grooves that had been previously worn in the journal box face by the corrugations on the lid, will be obliterated. In Fig. 8 there is shown a partial transverse sectional view through the housing member of the lid. Assuming one end of spring 29 to be in engagement with abutment 37 of the lever, the opposite end 52 extends slightly beyond abutment 38 of the housing when not in engagement therewith. When end 52 is forced into contact with abutment 38 the spring is placed under torsion. This torsion tends to rotate the closure member relative to the housing until one of stops 53 on the housing engages the adjacent surface on the closure member. Therefore, during successive closings of the lid the closure member will always be in the same position relative to the face of the box and any grooves that have worn into the face by corrugations 51 will be in alignment with said corrugations.

Stops 54 on the lower end of member 18 limit transverse tilting of the closure member to a pre-determined amount and still permit sufficient tilting to assure contact of the lid on both sides of the journal box opening.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A journal box lid comprising a closure member and a housing member, means for joining said members for a limited amount of universal pivotal movement comprising a spherical recess in said closure member and a spherical projection on said housing member received in said recess, a lever pivotally mounted in said housing member, spring means between an end of said lever and said closure member adapted through said lever, to maintain said projection in said

recess, and a substantially horizontal flange on said housing member extending outwardly of and overlapping said closure member in the region of said recess adapted to limit longitudinal movement of said closure member relative to said housing member in the event that said spring means becomes incapable of maintaining said projection in said recess.

2. A journal box lid comprising a closure member adapted to close the opening in one end of a journal box, a yoke extending outwardly from said closure member and formed with a spherical socket, said yoke having a substantially horizontal flange on each side of said socket extending outwardly of said closure member, a housing member having one end adapted to be pivotally secured to a journal box and having its other end formed with a spherical projection fitting into said socket, a lever pivoted intermediate its ends in said housing member for limited universal movement relative thereto, spring means between one end of said lever and said closure member adapted to force the other end of said lever against the hinge lug on a journal box, and means on said housing member extending outwardly therefrom on each side of and spaced from said flanges adapted to limit pivotal movement of said closure member relative to said housing.

3. In a journal box lid a housing member and a closure member, means joining said members for a limited amount of universal pivotal movement relative to each other, a lever pivotally mounted in said housing member, said lever being adapted to move bodily away from said housing member, spring means normally maintaining said lever in engagement with said housing member, and projecting means on said lever having an opening therein adapted to receive projecting means on said closure member to limit movement of said lever longitudinally of said housing member when said lever tends to move bodily away from said housing.

4. In a journal box lid a housing member and a closure member, means joining said members for a limited amount of universal pivotal movement relative to each other, a lever pivotally mounted in said housing member, said lever being adapted to move bodily away from said housing member, spring means normally maintaining said lever in engagement with said housing member, said lever having an opening therein and a projection on said closure member adapted to be received in said opening to limit movement of

said lever longitudinally of said housing member when said lever tends to move bodily away from said housing.

5. In a journal box lid a housing member and a closure member, means joining said members for a limited amount of universal pivotal movement relative to each other, a lever pivotally mounted in said housing member, said lever being adapted to move bodily away from said housing member, spring means normally maintaining said lever in engagement with said housing member, a projection extending downwardly from said lever, said projection having an opening therein and a projection on said closure member adapted to be received in said opening upon bodily movement of said lever toward said closure member to prevent loss of said lever due to breakage of said spring means.
6. A journal box lid comprising housing and closure members, a lever pivotally mounted in said housing member, coil spring means between said lever and closure member continuing along substantially the same helix throughout the entire extent thereof, and stop means on said lever and closure member adapted to engage the ends of said spring means to limit rotation about the longitudinal axis thereof.

7. A journal box lid comprising housing and closure members, a lever pivotally mounted in said housing member, coil spring means between said lever and closure member continuing along substantially the same helix throughout the entire extent thereof, and stop means on said lever and closure member adapted to engage the ends of said spring means to limit rotation about the longitudinal axis thereof said stop means being so positioned as to place said spring means in torsion when assembled in said members.

8. A journal box lid comprising a closure member and a housing member, means for joining said members for a limited amount of universal pivotal movement comprising a spherical recess in said closure member and a spherical projection on said housing member received in said recess, a substantially horizontal flange on said closure member on each side of said recess extending outwardly of said lid and a substantially horizontal flange on said housing member spaced from and adjacent each of said first named flanges adapted to engage said first named flanges to limit said pivotal movement of said closure member relative to said housing member.

ALBERT O. BUCKIUS.
